UNITED STATES PATENT OFFICE

2,550,121

GARMENT

Ruth E. Medd, Des Moines, Iowa

Application November 10, 1948, Serial No. 59,245

2 Claims. (Cl. 2—211)

1

The principal object of my invention is to provide a skirt or like garment that may be easily and quickly changed as to color or design.

More specifically, the object of this invention is to provide a striped pleated skirt or like that permits the individual pleat placement to the right or left for changing the general appearance of the same.

A still further object of my invention is to provide a changeable pleated skirt that is economical in manufacture, durable in use, and refined in appearance.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of my skirt ready for use.

Fig. 2 is an enlarged upper portion of the skirt and shows how the pleats are reversed.

Fig. 3 is a perspective view of my skirt with the pleats reversed from that shown in Fig. 1.

Fig. 4 is an enlarged top plan view of a portion of the skirt showing the control means for reversing a pleat.

Pleated skirts and like are very old and are universally used. Their objection, however, is that they are not changeable as to either design or color. I have overcome such problems, by providing a readily reversible pleat skirt and which I will now describe in detail.

The numeral 10 generally designates my skirt. Preferably it is made of a material having longitudinal color or design stripes. I have also found that most plaid fabrics work well. In the drawings and for illustrative purposes, I have used a fabric having two vertical longitudinal and contrasting color stripes 11 and 12. For better effect the stripes 11 are wider than the stripes 12, but any width or combination of stripes may be used. The numeral 13 designates the plurality of vertical pleats formed by the usual stitching 14 at their longitudinal bases. These pleats 13 are left loose to fold either to the left or right. In the drawings, these pleats have a width substantially one-half of the width of the stripes 12 and the stripes 12 start at the outer edge of each of the pleats. By this arrangement, if the pleats are all folded toward the stripes 12, the dress will all be of the color of the stripes 11, as shown in Fig. 1. If on the

2

other hand all the pleats are folded in the other direction, all the stripes 12 will show (with only parts of the stripes 11 showing) and a different skirt as shown in Fig. 3 will be produced. Obviously, if desired all kinds of effects may be produced. If desired, only a few pleats, either to the front, or sides, or back may be turned one way and all the other pleats turned the opposite direction. Or if desired, only every other, or every other two or more pleats may be turned in one direction and the others left to extend in the opposite direction. From this it will be seen that not only is the color change possible, but pattern design and panel arrangement are possible. To accomplish this manual pleat reversion, I secure a string, or like 15, to the outer left side of each pleat, and a string, or like 16, to the outer left side of each pleat, as shown in Fig. 4. Each of these strings are first passed through the waist band of the skirt, then through the outer edge of the pleat, and then back through the waist band at a different location than where it first pierced the waist band. The two ends of the string or yarn are then tied together as shown in Fig. 4, to prevent their removal. If a string 15 is pulled, it will obviously pull the pleat to which it is secured over and to that direction and a color or design is affected. On the other hand, if a string 16 is pulled, it will pull the pleat to which it is secured over and to that direction, and a different color or design will result. Thus it will be seen that a great variety of patterns, designs or colors may be had merely by the selection of strings one pulls. The strings passing through the waist band will experience enough frictional contact with the waist band to hold the string taut and the pleat flat.

If desired the outer marginal edge of each of the pleats may be stitched at 17 to better maintain the pleat.

Another advantage of my skirt is that when it becomes soiled either by use or accident, it is merely necessary to reverse the pleats to give a new clean appearance to the garment.

Some changes may be made in the construction and arrangement of my garment without departing from the real spirit and purpose of my invention, and it is my intention to cover by my claims, any modified forms of structure or use of mechanical equivalents which may be reasonably included within their scope.

I claim:

1. In a garment, a fabric base portion having a plurality of pleats each formed by sewing at

its longitudinal base; said pleats capable of being folded either to the left or to the right, a string means secured to the outer edge portion of each of said pleats and extending back through the fabric base portion to the right of the pleat to which it is secured, and a string means secured to the outer edge portion of each of said pleats and extending back through the fabric base portion to the left of the pleat to which it is secured.

2. In a device of the class described, a base fabric, a pleat formed in said base fabric capable of being folded either to the right or to the left onto the base fabric, a string means extending first through the base fabric at one side of said pleat, then through the outer edge portion of said pleat, then back through the base fabric at a point not common with the point it originally passed through the base fabric, a second string means extending first through the base fabric 20

at the other side of said pleat, then through the outer edge portion of said pleat, then back through the base fabric at a point not common with the point it originally passed through the base fabric, and a tie knot for closing the two ends of each of said string means.

RUTH E. MEDD.
